UNITED STATES PATENT OFFICE.

HARRY W. LASTER, OF OAK PARK, ILLINOIS, ASSIGNOR OF ONE-HALF TO C. H. WHITE,
OF CHICAGO, COOK COUNTY, ILLINOIS.

STREET-PAVING ROLLER.

Application filed June 8, 1925. Serial No. 35,525.

This invention relates to street paving rollers and its principal object is to provide a machine for rolling down asphaltic or other hard pavements during the laying thereof, and which will roll down the pavements without leaving any of the usual waves or undulations that result when the ordinary street paving roller is used. The invention has been designed particularly for use in connection with the rolling down of freshly laid asphaltic or like pavements on crowned streets and it is in such places that the tendency for the ordinary street paving roller to form waves or undulations is particularly noticeable. With the ordinary street roller having two rollers of the same width, there is a tendency for the machine to sway sideways, especially when passing along or near the crest of the crown of the street, and this swaying motion causes the outer ends of the rollers to sink into the soft pavement during the oscillations of the machine, thereby forming the objectionable waves or undulations in the surface of the pavement.

I have overcome this defect in street paving rollers by providing three spaced places of support for the machine, thereby overcoming its tendency to wobble or sway, and I have accomplished this by making one of the rollers in the form of a double roller or a roller having a double tread portion, whereby the double roller or double tread portion of one roller may have two spaced places of support and the other roller furnishes the third place of support. The invention, therefore, consists in a street paving roller having a single roller at one end of the machine and a double roller, or roller having a double tread portion, with a space therebetween at the other end of the machine, the width of the double roller and space therebetween, or the roller with the double tread portion and the space between the double tread portions being the same or substantially the same as the width of the other roller and the width of the space between the tread portions being relatively small. The invention further consists in the several novel features of construction and arrangement hereinafter fully set forth and particularly defined in the claims.

The invention is clearly illustrated in the drawing accompanying this specification, in which:

Fig. 1 is a side elevation of a street pav-

ing roller (in skeleton form) and showing a simple embodiment of my invention applied thereto; Fig. 2 is a plan of the rollers, the frame of the machine being illustrated in dotted lines; Fig. 3 is an end view of the double roller; Fig. 4 is an end view of the single roller and Fig. 5 is an end view of a slightly modified form of double roller.

Referring to said drawing and first to Figs. 1 to 4, inclusive, the reference character 6 designates the main frame of the machine which, as usual, is provided with a steering fork 7 at one end, swiveled in the frame upon a vertical axis and, if desired, said fork may be swiveled along a horizontal line as shown at 8. As is customary, suitable steering mechanism 9 is provided for steering the machine. The frame supports a power plant of some form, which may comprise a steam boiler 10 and a steam engine 11.

Journaled in the fork 7 is the steering roller 12 of the machine, and journaled at the other end of the frame 6 is the driving roller 13. The rollers are usually made of large diameter, sometimes measuring from four to five feet in diameter or more, and the width of rollers is sometimes made as great as four to six feet, although, of course, the sizes mentioned are not material to this invention broadly considered. As is well understood, the machine is a heavy structure intended to roll down relatively soft or freshly laid pavements. The driving roller 13 is operatively connected to the engine 11, by suitable driving gearing, as is well understood.

One of the rollers, as, for instance, the driving roller 13, is in the nature of a double roller, the total width between the outer sides of which is the same or substantially the same as the total width of the other roller 12. The exact construction of the double roller is immaterial and in the form shown in Figs. 1 to 3, inclusive, I have illustrated it as comprising a drum 14 of substantially the same width as the roller 12 and having secured thereon by rivets, bolts, or the like, two tires or bands 15, the outer edges of which coincide with the outer edges of the drum and the inner edges of which are spaced apart to leave a gap therebetween which is of less than one-half the width than either tire or band 15. The exact thickness of the tire is not material, but I have shown one that is approximately seven-

eighths of an inch in thickness. Said tires or bands 15 form two spaced apart tread portions for the roller 13 and to all intents and purposes act as a double roller, the two members of which are spaced apart a distance less than one-half the width of either tire or band 15, whereby the weight is distributed over practically all of the total width of the roller.

10 In the form of the invention illustrated in Fig. 5 the double roller 13^a comprises two separate rollers 15^a spaced apart a distance less than the width of either roller 15^a, the total width, however, of the double roller 15 and the space therebetween being the same or substantially the same as that of the other roller of the machine. In this form of the invention the two members of the double roller may have a differential gearing between them, operatively connected to the engine, as is well understood.

In the operation of the machine, it is driven over the relatively soft or freshly laid pavement in the usual manner and, because of the double roller arrangement, one end of the machine has two places of support, as is seen graphically in Fig. 3. This effectively prevents the machine from wobbling or swaying, especially when traveling along crowned pavings. When moving in the direction of the arrow *a*, in Fig. 2 the double roller leaves a slight ridge in the surface of the pavement, as illustrated in Fig. 3, but when the machine is driven in the direction of the arrow *b*, in Fig. 2, the full width roller 12 smooths down the ridge left by the double roller, leaving the surface in a smooth condition. It is understood that the machine is moved back and forth along the soft or freshly laid pavement a great many times during the rolling or smoothing process, and it is moved along parallel or substantially parallel over-lapping tracks or paths, and that during the rolling process the pavement material becomes hardened more or less, and is rolled down into a compact mass, and that as it becomes harder there is less tendency for the double roller to sink into the pavement, although the stability of the machine is maintained because of its three places of support upon the pavement. Furthermore, by reason of the great width of the bands as compared with the width of the gap between them, there is no tendency for the bands to form grooves or ruts in the pavement as is the case where the width of the gap between the bands is as great as, or greater than, the width of the bands. Such rollers may be used in rolling macadam pavements, but they would serve no useful purpose whatever in rolling

down asphaltic or other plastic, hard surfaces forming pavements, because of the grooves that would result from the use of relatively narrow bands.

65

From actual use in rolling down street pavements, I find that any tendency for the machine to wobble or sway has been entirely eliminated, and that it is possible to roll down the street pavements without leaving any waves or undulations therein, on the contrary, that a smooth and even surface is obtained on crowned street pavements as well as flat ones.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new, and desire to secure by Letters Patent:

1. A street paving roller, comprising in combination, a supporting frame having a fork swiveled thereto at one end, a steering roller journaled on said fork and a driving roller journaled on the other end of said frame, said driving roller having two closely spaced tread portions forming the major part of the tread surface of the roller, and the width of said first mentioned roller being substantially the same as the combined width of the two spaced tread portions of the driving roller and the space therebetween.

2. A street paving roller, comprising in combination, a supporting frame having a fork swiveled thereto at one end, rollers, one journaled on said fork and one journaled on the other end of the frame, one of said rollers having two spaced tread portions, the total width of said tread portions and space therebetween being substantially the same as the width of the other roller, and the space between said tread portions being less than one-half of the width of either tread portion whereby said tread portions form the greater part of the tread surface of said roller.

3. A street paving roller, comprising in combination, a supporting frame having a fork swiveled thereto at one end, a steering roller journaled in said fork, a driving drum journaled on the other end of the frame and two spaced tires secured on said drum, the total width of said tires and space therebetween being substantially the same as that of the steering roller, and the two tires comprising the major portion of the tread of the roller.

HARRY. W. LASTER.
